UNITED STATES PATENT OFFICE.

CLAUDIUS DORNIER, OF FRIEDRICHSHAFEN-ON-THE-BODENSEE, GERMANY, AS-
SIGNOR TO THE FIRM: ZEPPELINWERK LINDAU, GESELLSCHAFT MIT BESCHRANK-
TER HAFTUNG, OF LINDAU-REUTIN, GERMANY.

FLYING-BOAT'S HULL.

Original application filed June 15, 1921, Serial No. 477,843. Divided and this application filed May 10, 1924. Serial No. 712,368.

To all whom it may concern:

Be it known that I, CLAUDIUS DORNIER, a citizen of Germany, residing at Friedrichshafen-on-the-Bodensee, Germany, have 5 invented certain new and useful Improvements in Flying-Boats' Hulls, of which the following is a specification.

My invention refers to flying machines and more especially to a flying boat of the 10 type in which fins or stump wings are mounted laterally of the boat's hull and near the bottom thereof, in order to ensure an increased stability of the machine when resting on the surface of the water.

15 In the flying boat according to the present invention, these fins or stump wings taper in thickness from the hull towards their other ends, in order to increase the lateral buoyancy when assuming a laterally inclined 20 position, and the outer portion of each wing increases in thickness again, whereby the lateral buoyancy is increased still further.

25 In order to prevent the outer portions of the fins from being damaged by the impact of the waves, this portion may advantageously have the form of a separate boat's hull disengageably fixed to the fin or stump wing. This auxiliary boat's hull not only 30 protects the lateral edge of the fin against damage, but may also serve as life-saving means.

35 In the drawings affixed to this specification and forming part thereof, two flying boats embodying my invention are illustrated diagrammatically by way of example.

In the drawings—

40 Figs. 1 and 2 are a front elevation and plan view, respectively, the wing or bearing plane and the rear portions of the hull being partly broken away.

Figs. 3 and 4 are similar views illustrating a second modification.

45 Referring first to Figs. 1 and 2, 1 is the boat's hull, 2 is a self-supporting wing mounted on and extending across said hull, 3 and 4 are the motor and traction propeller, respectively, mounted in front of the wing and 5, 5 are a pair of fins or stump wings extending laterally of and near the bottom of 50 the hull. As shown in the drawings, these fins are thickest at their bases adjoining the lateral walls of the hull and their upper surfaces 6 extend substantially in horizon-

tal direction. Their lower surfaces are inclined relatively to the horizontal, rising 55 gradually in outward direction. Near the outer edge, however, each fin again increases in thickness and the outer portion 8 may be substantially as thick or even thicker than the base portion.

60 In the modification illustrated in Figs. 3 and 4, the formation of the fins is substantially the same as shown in Figs. 1 and 2, however, the thickened outer portion is formed in this instance by a small boat's 65 hull 8 detachably fixed to the lateral edge of the fin, the upper surface of this hull extending in line with the upper surface of the fin, while the bottom 9 of the small boat projects somewhat below the lower lateral edge 70 of the fin. As shown in Fig. 4, the lateral portion of each fin is shaped to correspond to the boat's hull 8 mounted thereon, this latter thus forming a smooth continuation 75 of the fin without appreciably projecting therefrom.

80 As can easily be guessed from the drawings, the fins, being mounted on the hull in a position where their bases are slightly above the water line, will serve for securely stabilizing the boat against lateral tilting, the displacement of the fin gradually increasing in outward direction. However, the thickened outer portion of each fin will 85 touch the water earlier than the middle portion, whereby a still greater lateral buoyancy is obtained.

90 I wish it to be understood that I do not desire to be limited to the exact details of construction shown and described, for obvious modifications will occur to a person skilled in the art.

I claim:—

95 1. A flying boat comprising a boat's hull, a fin or stump wing mounted on each side wall of said hull and first decreasing and thereafter increasing in thickness in lateral direction.

100 2. A flying boat comprising a boat's hull, a fin mounted on each side wall of said hull and extending substantially horizontally in lateral direction, said fin comprising a thick base portion, a thinner middle portion and a thick outer portion.

105 3. A flying boat comprising a boat's hull, a fin mounted on each side wall of said hull

and extending substantially horizontally in lateral direction, the upper surface of said fin extending substantially horizontally, the lower surface first gradually rising and thereafter dropping again in lateral direction, so as to form a fin with a thick base and outer portion and a thinner middle portion.

4. A flying boat comprising a boat's hull, 10 a fin or stump wing mounted on each side wall of said hull and decreasing in thickness

in lateral direction, a boat-shaped hollow body being disengageably mounted laterally of each fin, said hollow body being thicker in vertical direction than the adjoining portion of said fin. 15

In testimony whereof I affix my signature.

CLAUDIUS DORNIER.
